Primary Examiner — Sandra Snapp

CLAIM

The ornamental design for a dispensing device, as shown and described.

DESCRIPTION

FIG. 1 is an isometric view of a top, front, and left side of an ornamental design for a dispensing device;

FIG. 2 is a front elevational view of the dispensing device of FIG. 1;

FIG. 3 is a rear elevational view of the dispensing device of FIG. 1;

FIG. 4 is a right side elevational view of the dispensing device of FIG. 1;

FIG. 5 is a left side elevational view of the dispensing device of FIG. 1;

FIG. 6 is a top plan view of the dispensing device of FIG. 1;

FIG. 7 is a bottom plan view of the dispensing device of FIG. 1;

FIG. 8 is an isometric view of a top, front, and left side of another ornamental design for a dispensing device;

FIG. 9 is a front elevational view of the dispensing device of FIG. 8;

FIG. 10 is a rear elevational view of the dispensing device of FIG. 8;

FIG. 11 is a right side elevational view of the dispensing device of FIG. 8;

FIG. 12 is a left side elevational view of the dispensing device of FIG. 8;

FIG. 13 is a top plan view of the dispensing device of FIG. 8; and,

FIG. 14 is a bottom plan view of the dispensing device of FIG. 8.

The dash-dash-dash broken lines are for the purpose of illustrating environmental structure and form no part of the claimed design. In FIGS. 15-21, the surface shown in cross-hatching is of indeterminable length.

1 Claim, 12 Drawing Sheets
